Primary Examiner — George D. Kirschbaum*Assistant Examiner* — Maria J. Edwards(74) *Attorney, Agent, or Firm* — Foley & Lardner LLP(57) **CLAIM**

We claim the ornamental design for a housing for multiple valves, as shown and described.

DESCRIPTION

FIG. 1 is a front, right, perspective view of the claimed design, additionally showing an exemplary pair of valves attached to the housing, according to the present design; FIG. 2 is a front, right, perspective view of the claimed design of FIG. 1;

FIG. 3 is a front side view thereof;

FIG. 4 is a rear side view thereof;

FIG. 5 is a right side view thereof;

FIG. 6 is a left side view thereof;

FIG. 7 is a top view thereof; and,

FIG. 8 is a bottom view thereof.

The broken lines illustrate portions of the article and form no part of the claimed design.
